PLANER AND ATTACHMENTS THEREFOR

Richard A. Buttke, Milwaukee, Wis., assignor to Rockwell Manufacturing Company, Pittsburgh, Pa., a corporation of Pennsylvania

Original application Oct. 8, 1951, Ser. No. 250,345, now Patent No. 2,792,036, dated May 14, 1957. Divided and this application Sept. 28, 1956, Ser. No. 616,115

5 Claims. (Cl. 312—304)

The present invention relates to improvements in woodworking machinery and more particularly to improvements in the construction and structural arrangement of wood planing machines. This application is a division of applicant's application Serial Number 250,345, filed October 8, 1951, and now Patent No. 2,792,036.

An important object of this invention is the provision of a rigid, enclosed support base cabinet which is economical to manufacture and provides a firm, easily adjustable motor mount for the planer drive motor and a substantially dustproof housing for the drive motor to prevent the accumulation of wood dust and chips thereon.

This and other objects of this invention will become more fully apparent by reference to the appended claims and the following detailed description when read in connection with the accompanying drawings, wherein like reference numerals designate like parts and:

Figure 1 is a perspective view of an improved planer embodying the principles of my present invention;

Figure 2 is a plan view of the cabinet type base structure of my improved planer being in effect a horizontal section taken along the line 2—2 of Figure 3;

Figure 3 is a partially sectioned front elevation view of the base structure of the planer of Figure 1; and

Figure 4 is a fragmentary right side view of the planer base structure showing the adjustable drive motor mount.

The general structural arrangement of the improved planer of the present invention is shown in Figure 1.

This improved planer comprises a main base casting 20 from the opposite ends of which a pair of spaced columns 22 and 24 project upwardly. Column 22 is generally hollow in form and consists of three castings 25, 26 and 27, casting 25 being fixed to the base casting 20 and castings 26 and 27 being fixed to casting 25. Column 24 is also generally hollow in form and consists of a single casting 28, being fixed to the base casting 20. Base casting 20 rests upon a cabinet type, enclosed support structure 30 within which the planer drive motor is mounted.

A power driven cutter head and power driven parallel feed rolls extend between and are mounted for rotation at their ends on columns 22 and 24 near the top thereof. Below these feed rolls and this cutter head, which are not visible in Figure 1, a work support table 32, having a horizontal planar work support surface 34, extends between and is guided on columns 22 and 24 for limited translatory movement up and down between the columns 22 and 24 for adjusting the machine to accommodate pieces of lumber of different thicknesses. Vertical adjustment of table 32 is effected by a raising and lowering mechanism operated by manipulation of a handwheel 38 on the left side of the base casting 20. The position of the table 32 relative to the cutter head is indicated by the coaction of a pointer 40 fixed to the table 32 with a scale 42 fixed to column 22 parallel to the path of movement of table 32.

2

The cutter head is driven from the drive motor mounted within the support structure 30 by drive belts extending upwardly through base 20 and column 24 (Figure 2). The feed rolls are driven through a clutchable reduction drive mounted within the top portion of column 22 and driven from the cutter head (Figure 6). The engagement of the drive to the feed rolls is controlled by manipulation of a handle 44 which is fixed to a pivot shaft 46 projecting from the casting 27 of column 22.

The detailed structure of the foregoing parts of this improved planer will now be described in detail.

Cabinet type support structure and motor mount

Referring first to Figures 2, 3, and 4 the support structure 30, upon which the base casting 20 is mounted, is provided at its four corners with legs 48. Each leg 48 has an arcuate wall 50 (Figure 2), a bottom end wall 52 formed integrally on the inside of wall 50, and a top end wall 54, integrally formed on the inside of wall 50 at its upper end (Figure 3).

The front and rear side legs 48 are connected at their bottom ends by a tie bar 56, which is conveniently formed of angle iron. Tie bar 56 is rigidly secured at its respective ends to bottom end walls 52 of right front leg 48 and of right rear leg 48 by means of screws 58, which are threaded into the bottom end walls 52. The front and rear left-hand legs 48 are rigidly connected in the same manner by a similar tie bar 60.

Tie bars 56 and 60 are rigidly interconnected by means of front and rear tie rods 62 and 64. The tie rods 62 and 64 are rigidly connected at their ends to the vertical sides of tie bars 56 and 60 by screws 66 and 67 respectively. The four legs 48, the two tie bars 56 and 60 and the front and rear tie rods 62 and 64 are thus all rigidly connected together to form the skeleton frame upon which the base casting 20 of the planer is mounted.

The front and rear sides of support structure 30 consist of panels 68 and 69 preferably formed of sheet steel secured respectively between the two front and the two rear legs 48 by screws 70 threaded into ears 71 of legs 48 as shown in Figures 2 and 3. The right and left sides of support structure 30 consist of sheet steel panels 73 and 74 secured respectively between the two right and the two left side legs 48 by screws 75 threaded into ears 76 of legs 48.

The planer drive motor, designated 78, is supported within the cabinet 30 upon an improved motor mount which permits easy adjustment of the drive belt tension by raising or lowering the motor and also lateral adjustment of the motor. A sleeve 80 is rotatably received on rear tie rod 64 and is secured thereon against longitudinal movement between a pair of collars 82 and 84 fixed to tie rod 64 by set screws 85. The motor 78 is fixed to and supported by two brackets 86 and 88 which are of like longitudinal configuration best shown in Figure 4. The rear ends of brackets 86 and 88 are secured to sleeve 80 as by welding as shown in Figure 2. A cross bar 90 is secured between the upwardly offset forward portions of brackets 86 and 88 by bolts 92. A pair of eye bolts 94 and 96 are loosely received on front tie rod 62 and formed with threaded shanks 97 and 98 respectively, which pass upwardly freely through aligned holes in the ends of cross bar 90. The cross bar 90 is held in vertical position relative to the shanks 97 and 98 of eye bolts 94 and 96 between lower nuts 99 and upper nuts 100 threadedly engaged with the shanks 97 and 98.

The motor 78, being rigidly mounted on the brackets 86 and 88, will move pivotally about the axis of tie rod 64 with these brackets. The shaft 102 of motor 78 may

be adjusted vertically to either tighten or loosen the drive belts 104 passing around the drive pulley 106 fixed thereon by the cooperative adjustment of the nuts 99 and 100 on each of the eye bolts.

The motor 78 may also be moved laterally by loosening the set screws 85 of collars 82 and 84 and moving the motor 78 and sleeve 80 axially along the tie rods 62 and 64. This adjustment permits the use of various sizes of motors and makes it possible to vertically align the motor pulley 106 with the pulley on the cutter head.

As shown in Figure 3, the base casting 20 of the planer proper is mounted on this support structure 30 formed by the legs 48 and the front and rear panels 68 and 69 and the side panels 73 and 74 by a bolt 108 at each corner passing through a hole in the upper end wall 54 of each leg 48 and threaded into an aligned threaded hole in the base 20.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A support cabinet for a woodworking machine, comprising a pair of spaced parallel, cylindrical shafts of substantially equal length; a transversely extending tie bar rigidly fixed to the adjacent ends of said shafts at each of their ends; a corner leg casting fixed adjacent its lower end to each end of each of said tie bars and extending normal to the longitudinal axis thereof; a cover panel secured between each adjacent pair of said corner castings; a pair of cross bars extending between said shafts; means fixed to adjacent ends of said cross bars for mounting said cross bars for conjoint pivotal movement about and axial movement along one of said shafts; a pair of eye-bolts each slidably associated with the other of said shafts with their shank portions projecting upwardly therefrom; means for adjustably securing the other adjacent ends of said respective cross bars fixedly to said respective eye bolt shank portions; and means on said one shaft for fixing the axial position of said cross bar mounting means relative to said one shaft.

2. A support cabinet for a woodworking machine, comprising a pair of spaced parallel, cylindrical shafts of substantially equal length; a transversely extending tie bar rigidly fixed to the adjacent ends of said shafts at each of their ends; a corner leg casting fixed adjacent its lower end to each end of each of said tie bars and extending normal to the longitudinal axis thereof; a motor support structure pivotally and axially adjustably mounted on one of said shafts and pivotally connected to the other of said shafts and pivotal movement relative thereto; means for locking the adjustable connection between said support structure and said other shaft; and a cover panel secured between each adjacent pair of said corner castings.

3. A base cabinet for a machine tool comprising a first pair of spaced parallel bars of substantially equal length; a transversely extending tie bar rigidly fixed to the adjacent ends of said first pair of bars at each of their ends; said first pair of bars constituting the sole direct structural connection between said tie bars, a corner leg

member fixed adjacent its lower end to each end of each of said tie bars and extending normal to the longitudinal axis thereof; a cover panel secured between each adjacent pair of said corner leg members; a pair of cross bars extending between said first pair of bars; means fixed to adjacent ends of said cross bars for mounting said cross bars for conjoint pivotal movement about and axial movement along one of said first pair of bars; means pivotally and slidably associated with the other of said first pair of bars and having portions projecting upwardly therefrom; means for adjustably securing the other adjacent ends of said respective cross bars fixedly to said upwardly projecting portions; and means on said one of said first pair of bars for fixing the axial position of said cross bar mounting means relative to said one of said first pair of bars.

4. A base for a machine tool comprising a first pair of spaced parallel bars of substantially equal length; a transversely extending tie bar rigidly fixed to said first pair of bars at each of their adjacent ends to define therewith a rigid frame; said first pair of bars constituting the sole direct structural connection between said tie bars, an upstanding corner leg member fixed adjacent its lower end to each corner of said frame; a pair of cross bars extending between said first pair of bars; means fixed to adjacent ends of said cross bars for mounting said cross bars for conjoint pivotal movement about and axial movement along one of said first pair of bars; means pivotally and slidably associated with the other of said first pair of bars and having at least one portion projecting upwardly therefrom, means adjustably securing the other adjacent ends of said respective cross bars fixedly to said upwardly projecting portion; and means for fixing the axial position of said cross bar mounting means relative to said one of said first pair of bars.

5. A support cabinet for a machine tool comprising a pair of spaced parallel cylindrical shafts of substantially equal length; a transversely extending tie bar rigidly fixed to said shaft at each of their adjacent ends to define a rigid frame; an upstanding corner leg member fixed adjacent its lower end to each corner of said frame; a pair of cross bars extending between said shafts; means fixed to adjacent ends of said cross bars for mounting said cross bars for conjoint pivotal movement about and axial movement along one of said shafts; at least one eye bolt slidably associated with the other of said shafts with its shank portion projecting upwardly therefrom; means for adjustably securing the other adjacent ends of said respective cross bars fixedly to said tie bolt shank portion; and means on said one shaft for fixing the axial position of said cross bar mounting means relative to said one shaft.
